ATTORNEY

UNITED STATES PATENT OFFICE.

ARTHUR E. CLARKE, OF ARLINGTON, NEW JERSEY, ASSIGNOR TO CONGOLEUM-NAIRN, INC., A CORPORATION OF NEW YORK.

INLAID LINOLEUM.

Application filed February 8, 1923. Serial No. 252,704.

The present invention relates to floor coverings and to a process of manufacturing the same. More particularly does it relate to the manufacture of linoleum floor coverings having an inlaid vari-colored pattern simulating hand-laid tiling. 5

Among other objects my invention is intended to provide a novel, durable, and attractive inlaid linoleum having a color pattern formed in relief, and a novel and efficient method of producing the same. 10

The invention is particularly applicable to the manufacture of inlaid linoleum simulating hand-laid tiling, and will, therefore, be illustrated and described with particular reference to such embodiment, it being understood, however, that the invention is not so limited, but may also be embodied in other patterns. 15

20 In the drawing:

Figure 1 is a plan view of a piece of linoleum illustrating the successive steps in the process of its manufacture according to my invention.

25 Figure 2 is an enlarged section along the line II—II of Figure 1.

Figure 3 is an enlarged sectional elevation of the completed floor covering.

Referring to the illustrated embodiment of 30 the invention, numeral 1 indicates a suitable fabric base material such as burlap or canvas. Upon the fabric base 1, I apply a relatively thick layer of linoleum composition 2, which uniformly covers such base material. This

35 layer serves not only as a foundation upon which the inlaid color pattern may be formed, but in itself constitutes a portion of such inlaid color pattern. The layer of linoleum composition may be formed and united with 40 the burlap backing 1 in a single operation, by means of sheeting or calendering rolls in the usual manner of making mono-colored linoleum, or the sheet of linoleum composition 2 may be formed separately and thereafter 45 united, by pressure, with the backing. The linoleum composition layer 2 will usually be of a single color, which color will be chosen in a manner to simulate the mortar or other binder employed in hand-laid ceramic tiling.

50 The uniform linoleum sheet thus formed, may be partly cured or seasoned to increase its stability and toughness for the subsequent operations. However, if employed this preliminary seasoning should not be carried be-

yond the point at which the linoleum will 55 flow to a limited extent under the final consolidating pressure and at which the superimposed inlays of unseasoned linoleum composition will thoroughly bond therewith. In some cases, the partial seasoning may be dispensed with entirely and the freshly formed linoleum sheet employed directly in the subsequent operations. 60

Upon the uniform unseasoned or partially seasoned linoleum sheet thus produced, I 65 form the desired inlaid color pattern. According to my invention, I arrange upon the foundation layer 2, a plurality of blocks or tesserae 3, 4, simulating flooring tile, such blocks or tesserae preferably being cut or stamped from preformed unseasoned sheets of linoleum composition which are preferably, though not necessarily, of a thickness substantially less than that of the linoleum composition layer 2. As distinguished from 70 the ordinary type of block inlaid linoleum, however, the tesserae 3, 4 are positioned in non-contiguous relation providing narrow channels therebetween, whereby strips or portions 5 of the composition layer 2 are left 75 visible in the completed color pattern to simulate the mortar joints between the tiles. The inlaying process may be carried out by hand, if desired, although my invention facilitates 80 the application of the automatic rotary inlaying machines of the Walton type in the production of pattern linoleum of the type described. 85

The block inlays or tesserae 3, 4, simulating tile, are preferably, as indicated in the drawing, of varying colors or of different shades of the same color. For simplicity in illustration, I have shown inlays of two colors, although the number of different colors which may be utilized, is obviously not so limited. 90 Furthermore, the inlays of varying colors may be arranged in a regular manner as shown, or with an irregularity of occurrence simulating the irregular patterns of hand-laid tiling, such arrangement being a matter 95 of design. 100

The inlaid linoleum formed in the manner above set forth, is subjected to heavy pressure to unite the unseasoned blocks or tesserae 3, 4 with the layer of unseasoned or partially seasoned composition 2, to form a single integral mass. Simultaneously with the consolidation, the edges 7 of the blocks or tes-

seræ 3, 4 under the pressure being exerted, flow laterally to a limited extent and the exposed portions of the base layer flow upward, thereby causing such blocks to be im-
5 pressed into the surface of the foundation layer and the whole to assume the form or shape shown in Figure 3. In this manner, by suitably governing the pressure, the blocks and foundation layer are disposed at different
10 surface levels, and at the same time the variation in surface levels between the raised and recessed portions of the inlaid linoleum is formed with a smooth contour as shown at 8, thereby preventing the retention of dirt
15 and allowing the surface to be easily cleaned. I have found that satisfactory results may be obtained by effecting the consolidation according to the standard practice of consolidating straight line inlaid linoleum as illus-
20 trated in United States Patent No. 694,233 wherein the inlaid linoleum is pressed between a smooth-surface roll engaging the face of the goods and a heavy resilient blanket supported by a plurality of small-
25 diameter smooth-surface rolls. Where the inlays 3, 4, are of considerable thickness, how-
ever, it may become desirable to effect the consolidation with a suitably ribbed roll or plate whereon the ribs or raised portions
30 coincide with the channels or portions 5 of the completed color pattern. According to this latter practice, the ribs or raised portions of the consolidated roll or plate do not serve to indent or emboss, but simply to form a wall
35 of smooth contour against which the inlays 3, 4 may flow under the consolidating pres-
sure exerted, thereby assuring that the con-
tour of the recessed portions in the completed product will be of the desired configuration.
40 The consolidated product is then seasoned or cured by heat, according to well-known practice.

My invention provides a novel and efficient method for the manufacture of vari-
45 colored inlaid linoleum by the block inlay or "straight-line" process, which method avoids the major disadvantage of such products as heretofore known, that is, the susceptibility to breaking of the juncture of the inlays.
50 Thus, by constructing the floor covering with a unitary and uniform layer of linoleum com-
position 2 of substantial thickness forming a portion of the color pattern and serving as a foundation for the remaining portion of such
55 color pattern, I obtain a product which is of substantially uniform strength throughout and which will not tend to break or split along the juncture of the vari-colored inlays.

While I have illustrated the invention as applied to the manufacture of tile patterns, it may likewise be applied to the manufacture of other linoleum patterns as desired, and I do not wish to limit the scope of such invention except as defined in the following claims.
65 1. The method of making linoleum sim-

ulating tiling, which comprises forming a foundation layer of linoleum composition of substantial thickness and homogeneity ex-
tending continuously throughout the area of the intended product; forming separate in-
lays of linoleum composition, each simulat-
ing a tile; preparing the foundation layer and inlays to present plastic surface-portions capable of being welded together and in-
tegrated under pressure, and of permitting the inlays to be impressed into the surface of the foundation layer, and of permitting sur-
face-portions of the latter to flow somewhat under pressure; assembling inlays in sub-
stantially non-contiguous relationships in imitation of the arrangement of tiling, upon the plastic surface of the foundation layer, so that areas of the latter remain exposed between inlays to simulate mortar joints in tiling; applying pressure to impress the in-
lays into the surface of the foundation layer, and to weld and integrate the two, and to cause part of the foundation layer to flow into spaces between inlays; and governing the pressure to predetermine the relative im-
pressing of the inlays and flowing of the foundation layer, and to dispose the areas of foundation layer between inlays at a lower surface level than that of the inlays, while preserving beneath the inlays collectively a substantially continuous, integral, and homo-
geneous stratum of the foundation layer ma-
terial throughout the intended area of the product, whereby said stratum supplies a tough, durable, integral body for the product, independently of the bonds between the inlays and the foundation layer.

2. The method of making linoleum which comprises forming a foundation layer of linoleum composition of substantial thick-
ness and homogeneity extending continu-
ously throughout the area of the intended product, and having plastic surface-portions capable of permitting inlays to be im-
pressed into the surface of the foundation 110 layer, and of permitting surface-portions of the latter to flow somewhat under pres-
sure; assembling inlays in substantially non-
contiguous relationships upon the plastic surface of the foundation layer so that areas of the latter remain exposed between inlays; applying pressure to impress the inlays into the surface of the foundation layer, and to cause part of the foundation layer to flow into spaces between inlays; and governing 115 the pressure to predetermine the extent to which the inlays are impressed into the sur-
face of the foundation layer and to produce different surface levels of the inlays and those areas of the foundation layer that inter-
vene between inlays, while preserving be-
neath the inlays collectively a substantially continuous, integral, and homogeneous stra-
tum of the foundation-layer material throughout the intended area of the product, 120 125 130

whereby said stratum supplies a tough, durable, integral body for the product, independently of the inlays.

3. The method of making linoleum which 5 comprises forming a foundation layer of linoleum composition; forming separate inlays of linoleum composition; preparing the foundation layer and inlays to present plastic surface-portions capable of being welded 10 together and integrated under pressure, and of permitting the inlays to be impressed into the surface of the foundation layer, and of permitting surface-portions of the latter to flow somewhat under pressure; assembling 15 inlays in substantially non-contiguous relationships upon the plastic surface of the foundation layer, so that areas of the latter remain exposed between inlays; applying pressure to impress the inlays into the surface 20 of the foundation layer, and to weld and integrate the two, and to cause part of the foundation layer to flow into spaces between inlays; and governing the pressure to pre- 25 determine the relative impressing of the inlays and flowing of the foundation layer, and to dispose the areas of the foundation layer between inlays at a lower surface level than that of the inlays.

4. The method of making linoleum which 30 comprises forming a foundation of linoleum composition of substantial thickness having plastic surface-portions permitting inlays to be impressed into the foundation; assembling inlays in substantially non-contiguous relationships, upon the plastic surface-portions of the foundation; applying pressure to impress the inlays into the foundation and to produce different surface levels of the inlays and such portions of the foundation layer 35 as intervene between inlays, while preserving beneath the inlays collectively a substantially thick stratum of the foundation material which supplies a strong body for the product independently of the inlays.

45 5. The method of making linoleum which comprises forming a foundation layer of linoleum composition of substantial thickness; and forming inlays; the foundation layer and inlays having surface-portions 50 capable of being welded together and integrated under pressure, and of permitting the inlays to be impressed into the surface of the foundation layer, and permitting surface- 55 portions of the latter to flow somewhat under pressure; assembling inlays in substantially non-contiguous relationships upon the plastic surface of the foundation layer so that areas of the latter remain exposed between inlays; applying pressure to predetermine the relative 60 impressing of the inlays and flowing of the foundation layer, and to dispose at different surface levels the inlays and the areas of foundation layer between inlays, while preserving beneath the inlays collectively a stratum of the foundation layer material 65

which supplies a substantially integral body for the product independently of the inlays.

6. The method of making linoleum which comprises forming a foundation layer of linoleum composition; forming separate inlays 70 of linoleum composition; the foundation layer and inlays being plastic and capable of being molded and welded together and integrated under pressure, and of permitting the inlays to be impressed into the surface of the 75 foundation layer; assembling inlays in substantially non-contiguous relationships upon the surface of the foundation layer, so that areas of the latter remain exposed between inlays; impressing the inlays into the surface 80 of the foundation layer, and welding and integrating the two; and disposing at different surface levels the inlays and the areas of foundation layer between inlays; and molding projecting portions of the resulting 85 product to avoid abrupt corners on its surface.

7. As a new article of manufacture, a linoleum comprising a foundation layer of linoleum composition of substantial thickness 90 and homogeneity extending continuously throughout the area of the linoleum; separate inlays of linoleum composition embedded at least partially in the surface of said foundation layer, and welded and integrated therewith, said inlays being positioned in substantially non-contiguous relationship so that portions of the foundation layer are interposed and exposed between the inlays; the inlays and areas of the foundation layer be- 95 tween inlays being disposed at different surface levels; and the foundation layer having a continuous homogeneous stratum extending integrally beneath the inlays collectively 100 supplying a strong body for the linoleum in- 105 dependently of the bonds between the inlays and the foundation layer.

8. As a new article of manufacture, a linoleum comprising a foundation layer of linoleum composition; inlays embedded at least 110 partially in the surface of said foundation layer, positioned in substantially non-contiguous relationship so that portions of the foundation layer are interposed and exposed between the inlays; the inlays and areas of 115 the foundation layer between inlays being disposed at different surface levels; and the foundation layer having a substantially thick stratum extending beneath the inlays collectively 120 supplying a strong body for the product.

9. As a new article of manufacture, a linoleum comprising a foundation layer of linoleum composition; separate inlays of linoleum composition embedded at least partially in 125 the surface of said foundation layer, and welded and integrated therewith, said inlays being positioned in substantially non-contiguous relationship, so that portions of the foundation layer are interposed and exposed 130

between inlays; the inlays and areas of the foundation layer between inlays being disposed at different surface levels; and the foundation layer having a stratum extending substantially integrally beneath the inlays.

10. As a new article of manufacture, a linoleum comprising a foundation layer of linoleum composition; separate inlays of linoleum composition embedded at least partially in the surface of said foundation layer, and welded and integrated therewith, the inlays

being in substantially non-contiguous relationship on the foundation layer, so that portions of the latter are interposed and exposed between inlays; the inlays and the areas of the foundation layer between inlays being located at different surface levels; and the projecting portions of the surface of the product being devoid of abrupt corners. ¹⁵

In testimony whereof, I affix my signature.

ARTHUR E. CLARKE.
